UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

FRONT SIGHT FOR MILITARY SHOULDER-ARMS.

1,191,704.

Specification of Letters Patent.

Patented July 18, 1916.

Application filed February 12, 1916. Serial No. 77,828.

To all whom it may concern:

Be it known that I, THOMAS C. JOHNSON, a citizen of the United States, residing at New Haven, in the county of New Haven 5 and State of Connecticut, have invented a new and useful Improvement in Front Sights for Military Shoulder-Arms; and I do hereby declare the following, when taken in connection with the accompanying drawings and the characters of reference marked thereon, to be a full, clear, and exact description of the same, and which said drawings constitute part of this application, and represent, in—

15 Figure 1 a broken view in side elevation of the muzzle-end of a gun-barrel provided with a military front-sight constructed in accordance with my invention. Fig. 2 a view thereof in front elevation. Fig. 3 a 20 view thereof in vertical transverse section on the line *a*—*b* of Fig. 1. Fig. 4 a broken plan view of the muzzle-end of the barrel with the sight removed to show the key-slot. Fig. 5 a detached plan view of the 25 key. Fig. 6 a view thereof in side elevation. Fig. 7 a detached view in side elevation of the combined sight-base, over-arching sight-cover and barrel-encircling band. Fig. 8 a view thereof in rear elevation.

30 My invention relates to an improved front sight for military shoulder arms, the object being to produce a simple and reliable sight constructed with particular reference to ease of application to the gun-barrel as well 35 as to ease in the application and interchange of the sight-piece proper.

With these ends in view my invention consists in a front sight for military shoulder arms having certain details of construction as will be hereinafter described 40 and pointed out in the claims.

In carrying out my invention as herein shown, I employ a sight-base 2, an over-arching sight-cover or hood 3, and a barrel-encircling retaining-band 4, all made in one piece by suitable milling operations, the base 2 forming a web for uniting the cover or hood 3 and band 4 which latter is adapted to embrace the gun-barrel 5 which is made 45 with a very slight taper. The sight-base 2, hood 3 and band 4 thus form a combined part, easily handled and with its component features permanently fixed in relation to each other. Near its muzzle-end the 50 upper face of the barrel is formed with a

central longitudinal shallow key-slot 6 having rounded ends and designed for the reception of a key 7 having projecting rounded ends 8 between which it rises as at 9 above the upper face of the gun-barrel. 60 For the reception of the part 9 of the key 7, the sight-base 2 is formed in its lower face with a slot 10 running from rear to front and opening upward out of the top of the retaining-band 4 as best shown in Fig. 8. 65 A pin 11 passed through a transverse hole 12 in the sight-base 2 and also through a transverse hole 13 in the key 7, prevents the sight as a whole from moving either laterally or longitudinally with respect to the 70 gun-barrel. The upper face of the sight-base 2 is inclined as at 14 from rear to front, having a high point 15 at its rear end. This inclined face 14 is transversely intersected by a dovetail slot 16 inclined to 75 correspond to the inclination of the face 14 of the sight-base and receiving the dovetail rib 17 of the sight-piece proper comprising a body 18 and plate 19 both of which are thus inclined with respect to the line of the 80 gun-barrel owing to the inclined position of the slot 16, as described. For the insertion of the sight-piece proper, the sight cover or hood 3 is provided with aligned transverse openings 20 which permit the sight proper 85 to be readily applied to the sight-base 2 and interchanged with other sights of different heights as occasion may require. As shown, the rear face of the hood or cover 3 is roughened as at 21 to prevent its reflection 90 of light. The front and rear ends of the sight-base 2 are, as shown, though not necessarily, formed with deep cuts 22 and 23 which lighten the combined part.

I claim:—

1. A military sight having a sight-base, over-arching sight-cover or hood, and a barrel-embracing retaining-band, all made in one piece, in combination with a sight-piece applied to the said sight-base and located within the said over-arching sight-cover.

2. The combination with a gun-barrel having its muzzle-end formed with a key-slot, of a combined part comprising a sight-base, over-arching cover or hood, and a retaining-band, all made in one piece, a sight-piece applied to the said sight-base and located within the said over-arching-cover or hood, and a key set into the said slot and 110

co-acting with the said part for securing the same in place upon the gun-barrel.

3. A military front-sight having a sight-base, overarching sight-cover or hood, and a retaining-band, all made in one piece and formed in its upper portion with transverse openings, in combination with a sight-piece adapted to be passed through the said transverse openings for being positioned within 10 the overarching cover and applied to the said base.

4. A military front-sight having a sight-base, overarching sight-cover or hood, and a barrel-embracing retaining-band, all made 15 in one piece and provided in its upper portion with transverse openings and formed in the inclined upper face of the said base with a transversely arranged dovetail slot, in combination with a sight-piece having a 20 dovetail rib, the said sight-piece being

passed through one of the said transverse openings for location within the overarching sight-cover or hood, and application to the said base.

5. The combination with a gun-barrel 25 formed in the upper face of its muzzle-end with a key-slot, of a key fitting therein and extending above the upper face of the barrel, a one-piece combined part comprising a sight-base slotted to receive the said key, an overarching sight-cover or hood and a barrel-embracing retaining-band; means 30 passing transversely through the sight-base and key for holding the said combined part against lateral and longitudinal movement 35 with respect to the gun-barrel, and a sight-piece positioned within the said overarching sight-cover or hood and applied to the said base.

THOMAS C. JOHNSON.
